UNITED STATES PATENT OFFICE.

ARTHUR A. BARTON, OF CHICAGO, ILLINOIS.

PARACHUTE CONTROL.

Application filed November 4, 1921. Serial No. 512,758.

To all whom it may concern:

Be it known that I, ARTHUR A. BARTON, a citizen of the United States, residing at Chicago, in the county of Cook and State 3 of Illinois, have invented certain new and useful Improvements in Parachute Controls, of which the following is a specification.

My invention relates to means for controlling the descent of or landing place for a parachute to the end of avoiding a dangerous or unsuitable position to which uncontrolled parachutes so often descend or are carried by the wind. The object of 15 the present invention is to provide a valve whereby the initial part of a drop may be hastened in order to shorten a dangerous lateral drift, and to at the same time provide an adjustable rudder whereby such lateral 20 movement may be modified or changed.

With the foregoing object in view my invention consists in the novel construction of valve and rudder, its combination and arrangement of parts hereinafter described in 25 detail, illustrated in the accompanying drawing and more particularly pointed out in the appended claims.

In the drawing—

Figure 1 represents a side view of a 30 parachute, partly broken away, with my invention, shown partly in section, applied thereto.

Figure 2 is an enlarged plan view of the 35 valve-rudder and its frame alone, showing the valve-rudder in its closed position.

Figure 3 is an edge or side view of Figure 2, part of the upper clamp ring being broken away.

Figure 4 is an enlarged section taken substantially on the line 4—4 of Figure 2.

Figure 5 is a similar view taken on the line 5—5 of Figure 2.

In the several views 2 represents the body of the parachute which may be of any desired form of construction. In the middle or apex of the structure 2 is an opening 3 to the edges of which a valve and rudder frame is clamped, said frame consisting of a flat ring 4 between which and a clamping 45 ring 5, preferably semi-circular in cross section, the edges of the parachute at its opening are clamped. The ring 5 is narrower than the ring 4 and is clamped to the latter by means of bolts or other suitable fasteners 6, leaving an inner peripheral space 7 on which are mounted diametrically opposite

each other a pair of journal bearings 9 and 10 for valve-door journals or pivots 11 and 12 on a valve-door 13 which fits within the opening of the ring 4 and is preferably provided with a flat counterweight 14 with a curved edge 15 which overlies the inner edge —16— of the opening within the ring 4. The counterweight is thereby caused to serve as a stop limiting the rotary movement of 65 the valve while also tending to hold said valve in its closed position as in Figure 2. Each of said bearings 9 and 10 is secured by means of a plate or cover portion 17 thereon from which projects downwardly a slide 70 bearing-block portion 18 that is narrower than said plate portion 17 and passes through a curved slot in the ring 4. Against the under-side of the block 18 and loosely against the under face of the ring 4, is 75 placed a plate 19 of substantially the same dimensions as the plate 17. By means of bolts 20 passing through the parts 17, 18 and 19 these parts are held together slidably on the ring 4, nuts 21 on the bolts bearing 80 against the under plate 19. These bearing blocks 18 are movable in slots 22 and 23 which pass entirely through the plate 4 vertically. On the ends of one of the plates 19 are suitable rope or cable attaching means 85 such as eyes 24 and 25 and tangentially from said eyes similar eyes are secured to the under-side of the ring 4, an eye 26 being thus provided to co-operate with the eye 24 and a similar eye 27 being provided to co-operate with the eye 25 as a rope or cable 90 guide. While the arrangement is shown in its simplest form it is obvious that the usual pulleys or other guides may be provided in place of the eyes 26 and 27 as well as for 95 other similar eyes hereinafter referred to.

To the eyes 24 and 25, respectively, are secured the ends of ropes or cable, or other flexible connections, 28 and 29, the former passing from the eye 24 through the eye 26 100 from which the rope or cable hangs free in a run 30 which is extended downwardly to within reach of the parachute passenger (not shown) suspended in the usual manner from the parachute ropes or hangers —31— shown 105 partly in Figure 1. The valve 13 is swung on its axis or journals 11 and 12 by similar rope connections or their equivalents, the free or swinging edge of the valve or door 13 being for this purpose provided with an 110 eye 33 to which the ends of two runs of rope 34 and 35 are attached, the former hanging

down to within reach of the operator directly from the eye on the valve while the rope 35 is passed through an eye or pulley 36 from which a run 37 is extended to the operator. 5 By pulling on the latter the valve-door is closed, if or when it is necessary to assist its normal tendency to close owing to the counterweight aiding the substantially balanced air-pressure against the door during its 10 descent.

Pulling on the rope 30 swings the door in an arc at right angles to its 11, 12 axis and in one direction. In the opposite direction it is drawn by the rope 29 passing from the eye 15 25 through the eye 27 down to the operator in a run 32. The different angles of inclination at which the valve, door, or rudder 13 is held open or partly open determines the extent of lateral movement as well as rate of 20 speed of the dropping movement, the former being variable as to direction of lateral movement by swinging the member 13 at right angles to its axis 11 and 12. The journals 11 and 12 are held against longitudinal 25 movement in their bearings and the door adjusted to a proper fit within its opening by a pair of downwardly struck lugs 38 on the bearings 9 and 10 which act as end-thrust bearings.

I claim as my invention—

1. The combination with a parachute having an opening in its top, of a combination valve-door and rudder adjustable at various angles of inclination on an axis spanning said opening, and means for operating said valve-door and rudder. 35

2. The combination with a parachute, having a top opening, and a closer for said opening adapted to vary the velocity and direction of its descent, said closer being adapted 40 to swing angularly on a support which is rotatable in said opening.

3. The combination with a parachute, of a rudder-controlled passage therethrough, a rudder adapted to open and close said passage, said rudder being movable on a horizontal axis and means adjusting the angle 45 of inclination of said rudder.

4. The combination with a parachute having a vertical opening therethrough, of a door closing said opening in a horizontal plane, and means for adjustingly moving said door on two axes of rotation at right angles to each other. 50

In testimony whereof I have hereunto 55 signed my name.

ARTHUR A. BARTON.
